HIGH SPEED SPINNING

Masaye Kono, Nishinomiya, Japan

Application January 17, 1934, Serial No. 706,911
In Japan April 21, 1933

1 Claim. (Cl. 19—130)

The present invention relates to improvements in high speed spinning, which consists in somewhat condensing the roving before being fed to the back rollers and giving the fibres two to fifteen times draft between the back rollers and the succeeding middle rollers as they are passing in a parallel state.

Hitherto, only a small back draft (namely 1.05 to 1.3) has been able to be given to the roving between the back rollers and the succeeding middle rollers and most part of the draft is effected between the front and middle rollers, because the roving supplied to the back rollers is somewhat twisted, and if such a high draft were given there, there would be a fear of its disturbing the fibres and consequently causing the unevenness of thread.

An object of this invention is to provide a method of obtaining a considerably high draft between the back rollers and the next middle rollers providing means to restrain the roving in a somewhat condensed condition while diminishing unevenness and passing the roving between the back rollers and the middle rollers, both said rollers being suitably weighted.

Another object of this invention is to provide a method of obtaining an over-all draft considerably higher than by the ordinary means, combining said high draft of the first stage between the back and middle rollers with a high draft of the second stage between the front and middle rollers.

The accompanying drawing illustrates embodiments of the drawing apparatus for carrying out the method according to this invention, in which, Fig. 1 shows the general side view of a drawing frame;

Fig. 2, a modified embodiment of a drawing frame and

Fig. 3, a modification of a guide member for a roving.

Referring to the drawing, 1, 1' are a first pair of front rollers; 2, 2'; 3, 3', a second and third pair of middle rollers respectively and 4, and 4' a pair of back rollers. The rollers are so arranged that the distance between the third middle rollers and the back rollers has a certain length greater than the mean length of the fibre in order to perform draft from two to fifteen times and that the distance between the second and third rollers has a certain length smaller than the mean length of the fibre to be treated. The rollers other than the rollers 2, 2' are weighted as follows. 5 is a saddle mounted upon a front roller 1. Said saddle 5 is provided with a longitudinal slot 6 through which a supporting

arm 7 of a second saddle 8 is mounted adjustably on the saddle 5 by a pin 9. A bolt 10 fastened to the saddle 5 is also adjustable longitudinally. The head of the bolt 10 is provided with a recess to receive one end of a hook 11, the other end of which is connected to a lever 12 by means of a loop or a link 13. On one end of the lever 12 pivoted to a bearing 14 upon the frame 15 is suspended a weight 16 by a suitable means. A hand lever 17 is pivoted on the lever for supporting it upon the frame in order to release the rollers from the weights.

18 is a guide member for a roving supported by a traverse guide 19, arranged at a distance somewhat shorter than the fibre treated, from the nip of the back rollers 4 and 4'. The passage of the roving in said guide member is narrowed at the front half of it, and enlarged gradually towards the back end so that the restraining power may be exerted upon the roving as might happen between the pair of back rollers 4, 4'.

In this device, the roving, somewhat condensed between the guide tube and the bobbin, passes through the guide tube and receives the restraining action of said tube whose inner diameter at the delivery is somewhat smaller than the diameter of the roving, thus causing the fluffs to be attached closely to the surface of the roving and diminishing the unevenness of the same. Now, giving certain rotations to the rollers 3 and 3' and applying suitable weight upon the rollers 3' and 4', the roving may be drafted two to fifteen times which is the first stage of the draft. The roving next passes from between the second middle rollers 2 and 2' through the collector (not shown) to the front rollers 1 and 1' from which it is delivered. Between these two pairs of rollers, the roving is given a draft of 5 to 20 times, which is the second stage of the draft.

It may be clearly understood that such a high over-all draft may be obtained by the method according to this invention, considering that the present apparatus consists of two sets of drafting apparatus; namely, the rollers 1, 1', 2, 2', 3 and 3' as one set and the rollers 4, 4', and the guide member 18, as another set of drafting apparatus, the former set corresponding to a drafting mechanism of a ring spinning frame, and the latter set to that of an intermediate frame or of a roving frame.

Suppose that a 20's thread is to be spun with forty times draft and assuming the draft of first stage, as 4.5, that of second stage as 9, and the R. P. M. of the front rollers as 200, the number

of revolutions per minute of the back rollers should be only one fortieth of those of the front rollers, namely, 5 R. P. M., and those of middle rollers 3 and 3', 22, 5 R. P. M. Thus, it is clear 5 that the rollers 3 and 3' according to this invention effect the same draft upon the roving with only one-eighth revolution of the front rollers of the usual intermediate or roving frame, the R. P. M. of those frames being usually 170 10 to 180.

It is well known that the slower the rotation of the drafting rollers is, the more uniform the distribution or arrangement of the fibres of different lengths in the roving will be, if the draft 15 is kept constant. In the present invention the rotations of the drawing rollers 3 and 3' are very low as compared with those of the front rollers of the usual intermediate or roving frame. The 20 roving delivered from said rollers provides considerably uniform distribution of fibres with the favourable result that the thread spun by this machine is very strong and uniform in the quality.

This invention is also applicable to the drawing apparatus as shown in Fig. 2, in which *a*, *a'* 25 are a pair of front rollers; *b*, *b'* fixed supporters for revolving belts; *c*, *c'* a pair of middle rollers; *e* and *e'*, endless revolving belts respectively pass-

ing around the rollers *b*, *c* and *b'*, *c'*; *d*, *d'*, a pair of back rollers and *f* is a guide tube.

I claim:

A high draft mechanism for a spinning frame, comprising in combination, a pair of front rollers, 5 a pair of second rollers situated adjacent said front rollers, a pair of third rollers situated adjacent said second rollers, a pair of back rollers situated at a distance from said third rollers which is greater than the mean length of the 10 fibres to be treated, a guide tube having an orifice, the diameter of which is smaller than the mean diameter of the roving to be treated, a guide bar carrying said guide tube, said guide tube being situated behind said back rollers at a distance therefrom which is less than the mean 15 length of the fibres to be treated, and adjustable weighting means connected with said third rollers and said back rollers, the roving to be treated passing through the orifice of said guide tube and 20 then passing consecutively between said back rollers, said third rollers, said second rollers and said front rollers, the relative speeds of the rollers being such that a draft of two to fifteen is obtained in the first stage whereby the roving is subjected to two stages of comparatively high draft. 25
